UNITED STATES PATENT OFFICE.

ALFRED LEROI, OF FRANKFORT-ON-THE-MAIN, GERMANY.

FLOW-OFF AND SHUT-OFF DEVICE FOR TOILET CUPS.

1,413,858.

Specification of Letters Patent. Patented Apr. 25, 1922.

Application filed January 10, 1921. Serial No. 436,398.

(GRANTED UNDER THE PROVISIONS OF THE ACT OF MARCH 3, 1921, 41 STAT. L., 1313.)

To all whom it may concern:

Be it known that I, ALFRED LEROI, engineer, a citizen of German Republic, residing at Frankfort-on-the-Main, in the county 5 of Hessen-Nassau, State of Prussia (whose post-office address is Frankfort-on-the-Main, Mainzerlandstrasse 142), have invented certain new and useful Improvements in Flow-Off and Shut-Off Devices for Toilet Cups, 10 for which applications for patents were filed in Germany the 4th day of August, 1917 (D. R. P. No. 314,306), and the 18th day of September, 1920 (D. R. P. No. 342,597); and I do hereby declare the following to be a full, 15 clear, and exact description of the invention, such as will enable others skilled in the art to which it appertains to make and use the same.

This invention relates to an improved 20 flow-off and shut-off device for toilet-cups having, over the known art, the advantages hereinafter mentioned.

The accompanying drawing illustrates the subject matter of the present invention:

25 Fig. 1 is a perpendicular section through part of the toilet-cup embodying the flow-off and shut-off device,

Fig. 2 is a cross section on the line A—B of Fig. 1,

30 Fig. 3 is a cross section on the line C—D of Fig. 1,

Fig. 4 is a perpendicular section through the shut-off device in connection with a cylindrical strainer,

35 Figs. 5 and 6 show two other forms of strainer.

1 designates a toilet-cup having at its rear 40 wall a perpendicular cylindrical chamber 2 which is made in one piece with said cup.

45 The lower end of said chamber 2 is widened or enlarged and fitted, from below and outwards, with a metallic shell 4 having a tightening washer 5 toward said chamber. Said shell 4 has a lateral opening 9 which coincides with the outlet 3 of the cup 1 located at the lowermost point thereof and leading from said cup into said chamber 2 or said shell 4 respectively. In said shell 4 a tightly closing cylindrical shut-off body 10 is located and provided with an opening 11 corresponding to the opening 9 in said shell 4. Said shut-off body 10 carries an upwardly extending rod 12.

50 In the example illustrated, the upper end 55 of said rod 12 projecting beyond the usual

cover-plate of said cup 1 is supposed to be provided with an integral hand-lever (not shown) by means of which the shut-off body 10 can be turned on its own axis for 180° and thus into the position for closing the 60 outlet 3.

The shut-off body 10 may also be so adjusted that its plain wall closes the opening 9 in the shell 4, it being secured against turning by any suitable means. Upon the shut-off body 10 being then lifted by means of its rod 12, the outlet 3 is opened.

The improved shut-off device has the following advantages:—

1. by the insertion of the metallic shell 4 70 into the cup 1 from below a simple and easy accessibility of the shut-off device is attained, while after removal of the shut-off body 10 and of a flat strainer 13 arranged therein an easy cleaning of the chamber 2 75 is possible;

2. the metallic parts (shell 4 and shut-off body 10) can be kept as low as possible, which allows also a good and easy cleaning;

3. with one and the same design of cup 1 80 the adoption of a turnable or of a liftable shut-off device is possible, which simplifies the manufacture and storage.

Instead of a flat strainer 13 shown in Fig. 1, according to Fig. 4 a perforated 85 cylinder 23 may be employed, which, besides, may have the shape shown in Figs. 5 or 6. Said strainer 23 secures also the outlet 3 in such a way that liquid and very small foreign matters only can flow-off. The chamber 2 remains always free. If, instead of the cylindrical strainer 23 shown in Fig. 4, a strainer of the shape shown in Figs. 5 or 6, that is with closed perforated top and bottom or with closed perforated bottom only, 95 is employed, the chamber 2 is also secured through a straining device. The latter acts, however, in this case, as a bye-strainer only owing to the cylindrical surfaces of the strainer retaining large foreign matters, 100 which might pass through the outlet 3 and else obturate the chamber 2.

What I claim, is:—

1. In combination, a toilet-cup at its rear wall provided with an overflow and outlet 105 chamber having a lower enlargement therein and at its lowermost point with an outlet, a metallic shell inserted from below into said enlargement, a tightly closing shut-off body in said shell adapted to close the outlet 110.

in said cup, a strainer in said shut-off body, and means to operate said shut-off body, said shell and shut-off body being of low height and extending but little above said outlet substantially as and for the purpose set forth.

2. In combination, a toilet-cup at its rear wall provided with an overflow and outlet chamber having a lower enlargement therein and at its lowermost point with an outlet, a metallic shell inserted from below into said enlargement, a tightly closing shut-off body in said shell adapted to close the outlet in said cup, a cylindrical strainer in said shut-off body, and means to operate said shut-off body, said shell and shut-off body being of low height and extending but little above said outlet, substantially as and for the purpose set forth.

20 3. In combination, a toilet-cup at its rear wall provided with an overflow and outlet chamber having a lower enlargement therein and at its lowermost point with an outlet, a metallic shell inserted from below into said enlargement, a tightly closing shut-off body in said shell adapted to close the outlet in said cup, a cylindrical strainer in said shut-

off body having a closed perforated bottom, and means to operate said shut-off body, said shell and shut-off body being of low height and extending but little above said outlet, substantially as and for the purpose set forth.

4. In combination, a toilet-cup at its rear wall provided with an overflow and outlet chamber having a lower enlargement therein and at its lowermost point with an outlet, a metallic shell inserted from below into said enlargement, a tightly closing shut-off body in said shell adapted to close the outlet in said cup, a cylindrical strainer in said shut-off body having a closed perforated bottom and top, and means to operate said shut-off body, said shell and shut-off body being of low height and extending but little above said outlet, substantially as and for the purpose set forth.

In testimony whereof I affix my signature, in presence of two witnesses.

ALFRED LEROI.
